UNITED STATES PATENT OFFICE

LAURENCE M. OAKLEY, OF TRENTON, NEW JERSEY

DESIGN FOR A SHOE HEEL

Application filed August 5, 1930. Serial No. 36,559. Term of patent 7 years.

To all whom it may concern:

Be it known that I, LAURENCE M. OAKLEY, a citizen of the United States, residing at Trenton, in the county of Mercer and State of New Jersey, have invented a new, original, and ornamental Design for Shoe Heels, of which the following is a specification, reference being had to the accompanying drawing, forming part thereof.

Figure 1 is a bottom plan view of a shoe heel showing my new design, and Figure 2 is a section on the line 2—2 of Figure 1.

I claim:

The ornamental design for a shoe heel as shown.

LAURENCE M. OAKLEY.
